UNITED STATES PATENT OFFICE.

FRANKLIN PIERCE CAUBLE, OF LINCOLNTON, NORTH CAROLINA.

LIGHTNING-ARRESTER.

No. 882,096.

Specification of Letters Patent. Patented March 17, 1908.

Application filed May 3, 1906. Serial No. 315,020.

To all whom it may concern:

Be it known that I, FRANKLIN P. CAUBLE, a citizen of the United States, residing at Lincolnton, in the county of Lincoln and State 5 of North Carolina, have invented new and useful Improvements in Lightning-Arresters, of which the following is a specification.

This invention is a lightning-arrester, and has for its object an improved apparatus of 10 this kind embodying a choke-coil connected up in the line, and an insulated grounded conductor arranged within the coil and having the multiplicity of points extending in proximity thereto, to which the charge will 15 jump and thus pass to the ground.

In the accompanying drawing: Figure 1 is a plan view of the apparatus; Fig. 2 is a similar view with the cover removed; Fig. 3 is a cross-sectional view on the line 3—3 of 20 Fig. 1; Fig. 4 is a longitudinal sectional view on the line 4—4 of Fig. 2, with the cover replaced.

Referring specifically to the drawing, 10 denotes a casing having a base 11 from which 25 extend transverse end-walls 12, and a central longitudinal partition 13 connecting said end-walls. A cover is provided which comprises a top 14, ends 15 and sides 16, the latter of which extend down to the base and 30 form the side-walls of the casing. The end-walls 12 are spaced from the base as at 17, and are also recessed at opposite ends as at 18 for a purpose to be hereinafter described. The ends 15 are also recessed as at 19 which 35 recesses register with those at 18 whereby openings are formed in the end-walls of the casing through which the line wires enter. Between the end-walls, the base has openings 20, and in the bottom of the base are 40 transverse grooves 21. Extending from the sides 16 are bosses 22 having notches in which the screws or other securing devices, whereby the arrester is fastened to a support, are seated. The casing herein described will 45 be made of porcelain or other non-conducting material, and it contains and supports the working parts of the arrester to be herein-after described.

At 23 are indicated a pair of spools which 50 are made of porcelain or other non-conducting material, each spool having a central longitudinal opening 24 extending from end to end. The spools are also formed with a number of longitudinal slots 25 extending 55 from the outside to the openings 24. The ends of the spools are square as shown at 26

to form a support. The outside of the spools are formed with a spiral groove 27 in which the coils 28 are wound. Each opening 24 contains a conductor 29, preferably of carbon, and having radially-extending ribs 30 which fit in the slots 25. The depth of the grooves 27 is such that the coils do not touch the ends of the ribs 30, thus leaving said ends exposed, and forming a gap between the coil 60 and the ribs. The conductors 29 contain a core 31 of magnetized iron or steel which tends to cause the charge of lightning to jump with greater readiness from the coils to the conductors. 70

The ground wire is indicated at 32 being connected to a binding screw 33 located at one end of the base 11. Said binding screw is connected by a wire 34 to a second binding screw 35 at the other end of the base. The 75 wire 34 extends through a groove 36 in the bottom of the base. The connection between the binding screws and the conductors 29 is by metal plates 37 secured to the base 11 by the nuts 38 of the binding screws. The 80 plates 37 extend under the end-walls 12 through the spaces 17 and into the casing, and are bent upwardly as at 39 into contact with the ends of the conductors 29, said ends extending slightly beyond the ends of the 85 spools. Wires 40 connected to the line wires extend into the casing through the openings formed by the recesses 18 and 19, and are wound on the spools 23 to form the choke-coils, the same sized wire being employed. 90 If desired the line wires may be wound on the spools to form the coils whereby the arrester could be applied directly to the line without cutting it.

The apparatus herein described can be 95 used on grounded or metallic circuits. In the former case, a single coil and grounded conductor only need be used, and the casing can be made smaller to suit such form. The arrester will be secured to the cross-arm of 100 the pole or other support, it being especially designed for location outside of buildings, the casing affording ample protection in bad weather.

In use, when lightning strikes the line, the 105 charge traverses the coils and is diverted to the grounded conductors by jumping the gaps between the coils and the exposed ends of the ribs 30. The width of the gaps can be varied to suit different conditions by changing the depth of the grooves 27 or the length of the ribs 30. The openings 20 and grooves 110

21 effectively serve to prevent the parts from becoming smutted or disrupted, by allowing the blast or blow to escape through said openings. It is advisable, with lightning arresters used in outside work, that they be protected by a casing as nearly water-tight as possible, but nevertheless with outlets to prevent fracture or disruption of the parts by the discharge and the deposit of carbon or 10 "smut" on the parts in the casing.

I claim:—

A lightning arrester comprising an insulating spool having an axial bore, and slots

side of the spool; a grounded core in the 15 aforesaid bore, having radial ribs extending into the slots with their outer edges spaced from the outside of the spool; and a coil connected to the line, and wound on the spool out of contact with the aforesaid ribs. 20

In testimony whereof I have signed my name to this specification in the presence of two subscribing witnesses.

FRANKLIN PIERCE CAUBLE.
